CLAIM

The ornamental design for a computer device display screen with graphical user interface for an abdominal muscle stimulation system, as shown and described.

DESCRIPTION

The sole FIGURE is a front view of the computing device display screen with graphical user interface for an abdominal muscle stimulation system showing the new design. The broken lines showing an electronic device, the display screen, and elements of the graphical user interface illustrate portions of the article and form no part of the claimed design.

1 Claim, 1 Drawing Sheet
